UNITED STATES PATENT OFFICE

HERBERT V. HENDERSON, OF DETROIT, MICHIGAN, ASSIGNOR TO CHRYSLER CORPORATION, OF DETROIT, MICHIGAN, A CORPORATION OF DELAWARE

DESIGN FOR A RADIATOR SHELL

Application filed February 12, 1932. Serial No. 42,818. Term of patent 14 years.

To all whom it may concern:

Be it known that I, HERBERT V. HENDERSON, a citizen of the United States, residing in the city of Detroit, county of Wayne, and State of Michigan, have invented a new, original, and ornamental Design for a Radiator Shell, of which the following is a specification, reference being had to the accompanying drawings, forming a part thereof, in which:

Fig. 1 is a front elevational view of a radiator shell showing my new design.

Fig. 2 is a side elevational view of the same.
Fig. 3 is a plan view.

I claim:

The ornamental design for a radiator shell substantially as shown.

HERBERT V. HENDERSON.
